UNITED STATES PATENT OFFICE.

JOHN H. TRUMBULL AND HENRY TRUMBULL, OF HARTFORD, CONNECTICUT,
ASSIGNORS TO THE TRUMBULL ELECTRIC COMPANY, OF SAME PLACE.

ELECTRIC CUT-OUT.

SPECIFICATION forming part of Letters Patent No. 664,511, dated December 25, 1900.

Application filed April 17, 1899. Serial No. 713,232. (No model.)

To all whom it may concern:

Be it known that we, JOHN H. TRUMBULL and HENRY TRUMBULL, citizens of the United States, and residents of Hartford, in the county 5 of Hartford and State of Connecticut, have invented certain new and useful Improvements in Electric Cut-Outs, of which the following is a full, clear, and exact description, whereby any one skilled in the art can make 10 and use the same.

This invention relates to the general class of electric cut-outs in which a fusible connection is formed between a main line and a branch circuit, and is herein shown as applied 15 to a rosette commonly used to support the ordinary incandescent lamp from a wall or ceiling along which the main-line wires are located.

To this end our invention consists in the details of such parts and their combination, as hereinafter described, and more particularly pointed out in the claims.

Referring to the drawings forming part 20 hereof, Figure 1 is a view in side elevation of the improved cut-out with part broken away to illustrate the construction. Fig. 2 is a view in cross-section through the center of the base-piece of the cut-out with the contacts shown in full line. Fig. 3 is a plan view of the inner surface of the base-piece. Fig. 4 is a plan view of the inner surface of the cap. Fig. 5 is a detail view in cross-section through a part of the base-piece, showing a modified form of contact. Fig. 6 is a perspective view 35 showing the contact-arm that is borne by the cap.

In the accompanying drawings the letter *a* denotes the base-piece, which is made in the usual form and of insulating material, preferably porcelain. This base-piece has the usual openings *b*, through which screws or like fastening means extend for the purpose of securing the base-piece to a flat surface, and the openings are countersunk to receive the 40 heads of the screws. The contact-pieces *c* are located on diametrically opposite sides of the base-piece in suitable sockets *a'*, and they project a sufficient distance beyond the edge of the base-piece to enable the main wires to

be attached, as by means of clamp-screws *d*, 50 in the ordinary manner.

The contact-pieces *c* are held in the sockets, as by means of screws *e*, extending through openings in the base-piece, and in addition to the clamping means for holding the line-wire 55 they have preferably within the limits of the base-piece a loop *c'*, the opening through which is located transversely of the radius of the base-piece.

The cap *f* is made of porcelain or other insulating material, having the usual recesses on the inner face, within which are located contact-arms *g* and the fuse-clamps *h*. The contact-arms *g* are located on the cap in such position that when the base-piece and cap 60 are united the one on the other the raised portion of an arm will enter a socket *c'* in a loop *c'* and serve to bind the base-piece and the cap together by the spring action of the arm as well as by the positive engagement of 65 the parts. The contact-arm is provided at its outer end with a shoulder *g'* and near the bend of the arm with a stop *g''*, the distance between the stop and the shoulder on the end of the arm being substantially equal to the 70 width of the loop *c'*. The object of this construction is to hold the cap firmly against rotation in one direction, which is opposed by the stop *g''*, and with a yielding grasp in the other direction, movement in this latter direction being opposed by the frictional hold of the shoulder *g'* of the arm upon the edge of the opening *c'* through the loop *c'* in the contact-piece *c*. Each contact-arm is secured to the cap in any convenient manner, as by 75 means of screws, and through each arm also passes one of the screws *h* to hold the fuse. At the other end of each fuse-clamp the screw *i* serves as a means of binding the clamp upon the inner edge of the branch wire *k*. 80

As in the ordinary form of rosette, in connection with which our invention is shown as embodied, there are two contact-pieces on the base and two contact-arms corresponding and registering with the contact-pieces, but located on the cap. The projecting arms of the contacts *g* extend in a line transversely across the radius of the cap and in proper po- 95

sition to be thrust into engagement with the loops on the contact-pieces by a rotary movement of the cap, which is by preference centered by means of the short flanges *l*, located 5 on the opposite sides of the base-piece and adapted to engage the flange *f*' on the cap.

The latch device *g*' on the end of the contact-arm is formed by bending the material downward and then upward at the end of the arm, and in order to provide for the easier engagement and disengagement of the somewhat broad arm this latch *g*' is arranged at an angle with instead of squarely across the arm. The result of this arrangement is that 15 when the front end of the latch strikes the loop it rides up on the edge of the latch on what may be termed a "single" line rather than upon the whole surface across the breadth of the arm, as would be the case if 20 this latch were arranged so that its extreme end encountered and rested along the edge of the loop for the full breadth of the arm. On the application of force to unlock the parts the other end of the latch encounters the farther edge of the loop and is in the same manner lifted with less frictional resistance to the turning movement than if the latch was arranged directly across the arm.

In Fig. 5 a modified form of the improvement is shown as embodied in concealed work—that is, the cut-out is one in which the main wire is connected by means which do not cause it to show on the outside of the cut-out. In this latter form the numeral 1 designates the base of the cut-out, which is of insulating material, with the contact-piece 2 located in a socket wholly within the limits of the base-piece and having a tapered surface 3 on the end nearest the center of the base-piece, the clamp-screw 4 being seated in a threaded socket in the contact-piece and the usual washer arranged to be clamped down upon the end of the main wire 5, which passes through the hole 6 in the base-piece. Where 45 a single hole is provided for both of the main wires, a bridge 7 is left transversely across the hole, so as to provide means for keeping the inner ends of the main wire out of con-

tact with each other. It is obvious that two holes may be formed through the body of the porcelain instead of the single opening shown, if desired.

The form of attaching means in which our improvement resides provides a simple and extremely strong means for holding the cap 55 to the base, as the loop may be of any sufficient width to secure complete electrical contact between the parts while it holds the cap and the cover against accidental rotary movement in either direction, as already described. 60

We claim as our invention—

1. In combination in an electric cut-out, a base-piece, contacts on the base-piece each having a loop with a transverse opening and a clamp for a line-wire, a cap for the base-piece, contact-pieces on the cap with spring-arms that enter and engage the loop, the said arm being provided with a friction-catch at the outer end arranged in position to engage the loop, all substantially as described. 70

2. In combination in an electric cut-out, a base-piece, contacts on the base-piece each having a loop with a transverse opening and a clamp for a line-wire, a removable cap for the base-piece, contact-pieces on the cap with spring-arms that register with and engage respective loops, the arms being provided with a stop and on the outer end a latch located at an angle across the arm, all substantially as described. 75

3. In combination in an electric cut-out, a base provided with contacts for the line-wires, and a cap removably secured to the base-piece, each contact on the base-piece having a projecting loop with a transverse opening, 85 and the cap having contact-pieces that register with the contact-pieces on the base and have a spring-arm adapted to enter and lie within the socket in the loop, and a stop arranged to engage the loop.

JOHN H. TRUMBULL.
HENRY TRUMBULL.
